RADIAL CYLINDER ENGINE

Harry C. Dunning, Columbus, Ohio

Application September 10, 1951, Serial No. 245,856

4 Claims. (Cl. 121—120)

1

This invention relates to engines or motors of the type in which a working fluid is expanded in cylinders disposed radially of the crank shaft or longitudinal axis of the engine.

An object of this invention is to provide a radial cylinder engine in which steam, or other equivalent expansible working fluid, is, through the operation of an improved reciprocatory valve mechanism, introduced at timed intervals into the ends of the cylinders to effect, through expansion of the fluid, piston reciprocation.

It is another object of the invention to provide a radial cylinder engine in which piston reciprocation is effected by the employment of an expansible working fluid produced exteriorly of the engine and introduced into the engine cylinders through an improved reciprocatory valve mechanism actuated by the operation of the engine crank shaft.

Another object of the invention is to provide an engine of the character set forth in which reciprocatory valve mechanism, admitting a working fluid into the engine cylinders, is actuated by an adjustable cam plate mechanism, which is rotatably driven through the engine crank-shaft.

Still a further object of the invention is to provide in an engine of the character set forth a manually operated means for varying the longitudinal positions of operation of the cam plate mechanism to govern the port opening and closing movements of the slideable steam-admitting valves, and, additionally, controlling the operation of said valves to reverse the direction of rotation of the engine or motor shaft.

The invention disclosed in this application constitutes a continuation-in-part of the disclosure contained in my prior application, Serial No. 177,454 filed August 3, 1950, now abandoned.

For a further understanding of the invention, reference is to be had to the following description and the accompanying drawings, wherein:

Fig. 1 is a vertical longitudinal sectional view taken through a radial cylinder steam engine formed in accordance with the present invention;

Fig. 2 is a vertical transverse sectional view taken through the radial cylinders of the engine on the plane indicated by the line 2—2 of Fig. 1. In this figure, there is disclosed the sliding pistons of the engine and the connecting rods uniting the pistons with the associated engine crank shaft.

Fig. 3 is a similar view taken on the plane indicated by the line 3—3 of Fig. 1 and disclosing more particularly the crank shaft carried wobble plate mechanism for governing the operation of the engine valves;

5

Fig. 4 is a transverse sectional view taken on the plane indicated by the line 4—4 of Fig. 3, and disclosing the manually operated means for varying the operating positions of the wobble plate assembly in controlling and reversing the direction of rotation of the engine crank shaft;

10

Fig. 5 is a similar view on the plane disclosed by the line 5—5 of Fig. 1, setting forth improved adjustable cam means for controlling the longitudinal positions of adjustment of the wobble plate carrying sleeve in governing the timing of the slideable steam-admitting valves;

15

Fig. 6 is an enlarged detail vertical longitudinal sectional view taken through the wobble plate assembly and the union between the same and the steam-admitting valves;

20

Fig. 7 is a detail vertical sectional view on the line 7—7 of Fig. 5, disclosing the motion-transmitting gearing employed in governing the cam adjustment of the wobble plate sleeve;

25

Fig. 8 is a vertical transverse sectional view on the line 8—8 of Fig. 1, setting forth the crank shaft carried drive collar and the adjustable slotted union between said collar and the sliding clutch fingers on one end of the wobble plate sleeve.

30

Referring more particularly to the specific embodiment of my improved radial cylinder engine, as the same has been illustrated herein, the same comprises a casing, including a cylinder section 10, a valve section 11, a cam plate housing section 12, a front bearing section 13 and a rear bearing section 14. These sections are adapted to be bolted or otherwise securely united to produce a rigid assembly in which the various internal parts of my improved engine are contained. I do not, however, restrict myself to the precise details respecting the formation of these sections nor the manner of joining the same.

35

Arranged axially and longitudinally of the casting structure for rotation therein is a crank shaft 15. This shaft is also of sectional construction, as indicated by the sections 15a and 15b. The section 15a generally possesses a greater diameter in transverse cross section than the section 15b. In this instance, the section 15a is supported for rotation in connection with anti-friction bearings 16 which are arranged in a chamber 17 provided in the front bearing section 13. Also, the front bearing section is formed with a bore 18 receiving an oil ring 19, packing rings 20 and a clamping nut 21, the latter being accessible from one end of the bearing section 13 to control the compaction applied thereby to the packing rings 20. A lubricating oil may be admitted under pressure from an oil pump or other source of sup-

2

3

ply, not shown, by way of a pipe 22. The latter extends into a transverse passage 23 formed in the bearing section 13 and communicates with ports provided in the ring 19, oil under pressure being conducted axially through the crank shaft section 15a by way of the passages indicated at 24.

The inner end of the section 15a of the crank shaft terminates in a crank member 25. The outer end 26 of this crank member is of reduced diameter and is received in a socket 27 provided in the complementary inner end 28 of the crank section 15b, the two sections of the crank shaft being rigidly united to produce in effect a single composite structure.

The separation of the crank shaft admitted by the crank member 25 and the socket construction 27 provides for the convenient mounting of a connecting rod assembly on the crank member. In the specific form of the invention illustrated, which it will be understood may be widely varied, the connecting rod assembly provides an axial bearing sleeve 29 and spaced outer disks 30. Between the disks 30, there is fastened the inner end of a master connecting rod 31, the latter being secured to said disks by means of a pair of bolts 32, which are headed at one end, having an opposite end of each screw threaded for reception in openings formed in one of the disks 30, thereby rigidly uniting the inner end of the master connecting rod with the crank assembly provided by the disks 30, the sleeve 29 and the crank member 25.

The outer end of the connecting rod 31 is provided with a spherical enlargement 33, which is received in a semicircular socket formed in a thrust plate 34 which is carried by the inner or under side of a master piston 35, the latter being arranged for sliding movement in one of a plurality, in this instance eight, radially disposed cylinders 36 formed in the cylinder section 10, and which are arranged symmetrically about the crank shaft 15. The spherically enlarged end 33 of the master connecting rod is held in firm but movable engagement with the semispherical surface of the thrust plate 34 by a nut 37, which is screw threaded into the piston 35 and engages with a thrust washer 38 so that when the nut 37 is tightened, the enlargement 33 of the rod 31 is securely retained in operating contact with the plate 34.

Similarly, corresponding pistons 35a are provided in each of the remaining cylinders of the casing section 10, as shown in Fig. 2. The pistons 35a are joined with the outer ends of auxiliary connecting rods 31a, which possess the same configuration as the master connecting rod. The inner ends of the rods 31a are united with knuckle pins 39 joined with the disks 30 and disposed in relatively parallel relationship. The connecting rods 31 and 31a may be centrally bored to provide lubricant passages which communicate with the lubricant passages of the crank shaft.

The outer ends of the radial cylinders 36 are closed by means of detachable heads 40. Connected with these heads are threaded nipples 41 joined with the ends of steam conducting pipes 42, the latter leading from the valve section 11 of the casing structure and are employed to transmit an elastic working fluid, such as steam, from a suitable source of supply to the cylinders 36 for expansion in the latter in producing piston reciprocation. Each of the cylinders midway of its length is formed with a row of exhaust ports 43. By means of these ports, spent steam, follow-

4

ing predetermined expansion and piston movement, is caused to escape and transmitted to a circular exhaust manifold indicated at 44, which is bolted or otherwise secured to the front side of the casing section 10.

Steam, or other elastic fluid, obtained from any suitable generator, such as that set forth in my above-identified copending application, is transferred by way of a pipe line 45 to an annular chamber 46 formed in the valve section 11 of the casing structure. The chamber 46 is disposed in a substantially vertical plane, and is intersected by a plurality of horizontally extending parallel bores 47, corresponding in number with that of the cylinders 36. Positioned in each of the bores 47 is a sleeve 48, which is flanged at one end, as indicated at 49.

Slidably positioned in each of the sleeves 48 is a reciprocatory spool-type balanced valve 50. Each valve is formed to include headed ends, indicated at 50a and 50b, which are united by a stem 50c of reduced diameter, each of the heads being advantageously equipped with piston rings 50d having engagement with the inner walls of the associated sleeve 48. Each of the sleeves is formed with openings 51 which register with the chamber 46, so that when an associated valve occupies the position shown at the top of Fig. 1, steam, or other expansible fluid, is transmitted from the source of steam supply through the valve assembly and thence to one of the cylinders 36, in which the piston 35 therein is shown at the outermost position of its stroke. Steam so admitted into a cylinder 36 expands, thereby causing the piston 35 therein to move inwardly of the cylinder and, through its associated connecting rod mechanism, apply rotating power to the crank shaft. Mechanism, as hereinafter defined, is utilized for controlling the sliding movement of the valves 50 in effecting the desired timing of their operation in supplying steam to the working cylinders. Also, the valve mechanism functions at required period or periods for curtailing the steam supply, as will be presently explained.

Centrally, the valve section 11 is formed with a socket 52 which surrounds the section 15b of the crank shaft. This portion of the crank shaft is supported by means of ball bearings 53, or their equivalents, supporting the shaft for rotation in the longitudinal center of the casing structure. Additionally, the rear bearing section 14 of the casing structure is provided with one or more similar ball-bearing assemblies 54 for supporting the rear and outwardly projecting end of the crank shaft. The bearing section 14 includes a compressible packing 55 which surrounds the outwardly projecting end of the crank shaft and seals the rear end of the casing structure, in the same manner as the front end thereof is sealed by the packing 20. An adjustable follower 56 is carried by the bearing section 14 and bears on the packing 55 to control compaction thereof about the crank shaft.

To govern the operating adjustments of the slide valves 50 and to effect the timed reciprocation thereof, there is mounted on the crank shaft for rotation therewith, as by means of set screws 57, a collar 58. As shown in Figs. 1 and 8, this collar is formed with parallel openings 59, in which are slidably received relatively spaced and longitudinally extending tongues 60 which project from the rear end of a cam plate mounting and driving sleeve 61. Keyed, as at 62, upon the sleeve 61 is a slidable and rotatable collar 63. Pivotally connected as at 64 to the collar 63 is a link

65, the forward end of which being pivoted by a pin 66 or the like to a ring-shaped cam or wabble plate assembly 67. This assembly is used in imparting reciprocatory movement to the steam flow controlling valves 50, and to this end each of the valves 50 has its rear end formed with an extension tongue 68, the latter being provided with an opening in which is seated a ball 69, as shown more particularly in Fig. 6. The cam or wabble plate assembly includes an annular raceway in which the ball elements 69 are seated, the raceway being formed in the main ring 70 of the assembly 67, and in an associated and separable clamping ring 71.

Normally, the cam or wabble plate assembly assumes the operating position disclosed in Figs. 1 and 6, in which the same occupies an operating plane adjustable angularly to the vertical. As the assembly 67 rotates by the action of the drive collar 58, the sleeve 61, the sliding collar 63 and the links 65, reciprocatory movement is imparted to the steam valves 50, causing the heads 50a and 50b of said valves to cover and uncover the steam flow governing ports formed in the sleeves 48.

To adjust this mechanism, in order to control the timing of the valves 50 in admitting steam into the cylinders 36 from a source of supply and cutting off the same at the desired period for cylinder expansion, the sleeve 61 is formed with integral spaced circular flanges or webs 72, the latter defining between them an annular groove 73. Arranged in this groove are bars 74 which are formed with cylindrical longitudinally extending open-ended bores for the reception of eccentric rods 75. These rods have their ends journaled in bearings 76 formed in the walls of the housing section 12 of the casing assembly, as shown in Fig. 5. Motion is transmitted between these rods so that both of the same will be rotated simultaneously by the provision of intermeshing spur-toothed gears 77, disclosed more particularly in Figs. 5 and 7. One end of the uppermost of the rods 75 is extended through a packed bearing 78 to the exterior of the housing section 12, and has its outer end connected with an operating lever 79. Intermediately of its length this lever has fastened thereto a pivoted detent 80 having a foot 81 which is adapted for selective reception in notches 82 provided in a stationary quadrant member 83.

By removing the foot 81 from engagement with one of the notches 82, the lever 79 may be oscillated manually, rocking with it the upper of the eccentric rods 75, this rocking movement being imparted to the lower of the eccentric rods through the train of gearing disclosed at 77. Due to the eccentricity of the rods 75, movement thereof pushes the sleeve 61 forwardly or backwardly on the crank shaft, and this movement is in turn imparted to the cam or wabble plate assembly, which advances or retracts the valves 50 in their respective sleeves in governing the period of port opening and closure.

In order to reverse the direction of rotation of the engine shaft, the cam or wabble plate has its main ring 70 pivotally mounted for turning movement on stud trunnions 84 projecting from the sleeve 61, as shown in Figs. 1 and 3. By sliding the collar 63 longitudinally on the sleeve 61, the cam assembly may be rocked about an axis afforded by the trunnions 84, varying the angularity of the assembly. This enables the crank shaft of the engine to operate at different speeds, and to effect reversal when desired 75

in the direction of rotation of the crank shaft.

To move the sliding collar 63 in controlling the operating positions of the cam plate assembly, there is provided, as shown in Fig. 4, a horizontally extending rock shaft 85, which is journaled in bearings 86 formed in connection with the walls of the housing section 12. One end of the rock shaft projects beyond the housing section and has fastened thereto the lower end of a manually operated control lever 87. Normally, this lever is maintained in the upright position illustrated in Fig. 1 by the provision of a coil spring 88 or its equivalent. In this instance, the spring surrounds a sliding stem 89. One end of this stem is secured to the control lever while the other end thereof slidably projects in an opening provided in a bracket extension 90 formed stationarily with the section 12. By pushing on the upper end of the lever 87, the rock shaft 85 may be oscillated.

This shaft carries a fixed depending yoke 91, which is supported for oscillation within the confines of the casing section 12. The lower ends of the yoke 91 are slotted to receive pivotally movable bearing blocks 92, which are supported for rocking movement on the outer ends of headed studs 93. The inner ends of these studs are united with separable semicircular ring-forming elements 94 which are positioned in an annular groove 95 formed in the sliding collar 63.

Thus by rocking the lever 87 against the resistance offered by the spring 88, corresponding rocking movement is imparted to the yoke 91 to cause sliding movement of the collar 63 on the sleeve 61. Through the link element 65, such sliding movement of the collar 63 is imparted to the cam or wabble plate assembly so that the latter may be rocked to move between operating positions disposed equidistantly on opposite sides of a vertical or perpendicularly disposed plane passing through the pivotal supporting trunnions 84 of the cam or wabble plate assembly. When the cam plate assembly is disposed in a plane coinciding with said vertical plane, rotation of the assembly will not produce reciprocation of the steam flow-controlling valves 50. When the assembly is rocked to assume an extreme angular position, exactly opposite to that illustrated in Fig. 1 of the drawings, the valves will be operated to produce a reversal in the direction of rotation of the crank shaft with respect to that obtained by the parts when arranged as in Fig. 1.

While I have shown and described a preferred form of my improved engine construction, it is to be understood that various modifications may be made therein without departing necessarily from the spirit and scope of the invention.

I claim:

1. A fluid-actuated motor, comprising a casing, a shaft rotatably supported by said casing and extending longitudinally of the axis thereof, said casing being formed with a plurality of radially disposed piston cylinders, the latter being closed at their outer ends and having their inner ends 60 in open communication with a crank chamber formed in said casing, a crank forming a part of said shaft and rotatable in said chamber, pistons slidably mounted in said cylinders, a collar assembly surrounding said crank, connecting rod means extending from said collar assembly to each of said pistons, said casing being formed with a plurality of open-ended valve chambers arranged in circularly spaced relationship concentric with the axis of and extending 65 parallel to said shaft, means for conducting an

expansible working fluid under pressure from a source of supply to said valve chambers, valves slidably mounted in said chambers, wabble-plate means disposed within said casing concentric to and actuated by the rotation of said shaft for imparting sliding movement to said valves, fluid inlet connections leading from said valve chambers to the closed ends of said cylinders and operative when said valves occupy one position of operation in said cylinders to admit regulated quantities of the expansible fluid into said cylinders to effect operation of said pistons, and exhaust means communicating with said cylinders and operative upon predetermined travel of said pistons on power-delivering strokes to open and exhaust spent fluid from said cylinders.

2. In a radial cylinder steam engine, a casing formed with valve, cylinder, and control sections, said cylinder section being provided with a plurality of symmetrically arranged relatively spaced radially extending cylinders, each of the latter having a closed head at the outer end thereof and with the inner end of each cylinder opening to an internal crank chamber formed in said cylinder section, a shaft rotatably supported in said casing, said shaft including a crank rotatable in said crank chamber, pistons slidably mounted in said radially disposed cylinders, connecting rod means uniting said shaft crank with said pistons, said valve section being formed with a plurality of spaced parallel longitudinally extending open-ended chambers, valves having spaced heads united by stems of reduced diameter slidably positioned in said valve chambers, passage means controlled by the operating positions of said valves in said chambers for supplying an elastic working fluid under pressure to the headed ends of said cylinders, exhaust means for removing the expanded working fluids from said cylinders following predetermined movement of the pistons in said cylinders and expansion of said working fluid, a rotatable wabble plate assembly mounted in the control section of said casing, means for rotating said wabble plate assembly in unison with said shaft, means joining said assembly with said valves to produce predetermined reciprocatory movement of said valves in response to rotation of the wabble plate assembly, means supporting said wabble plate assembly to maintain the same in different planes of operation with respect to the vertical, and manually operated means for adjusting and maintaining the adjustment of said wabble plate.

3. In a steam engine, a casing assembly comprising: separably united cylinder, valve, control and bearing sections, said cylinder section being formed with a plurality of radially disposed cylinders, a shaft having a crank rotatable in said cylinder section in registry with said cylinders, bearing means carried by said bearing sections rotatably supporting said shaft, pistons slidably mounted in said cylinders, connecting rod means uniting the crank of said shaft with said pistons, said valve section including a central vertical web

formed with a plurality of open-ended chambers, the latter being arranged in circularly spaced relationship concentrically with respect to the axis of and extending parallel to said shaft; slideable valves carried by the chambers of said valve section, means governed by the operating positions of said valves providing for predetermined delivery of an expansible working fluid in timed order into said cylinders, means for exhausting said fluid from said cylinders following expansion thereof, a variable plane rotatable valve-operating wabble plate assembly revoluble with said shaft, said assembly being disposed in said control section, means joining said valves with said assembly to produce sliding motion of the valves in said chamber upon rotation of said assembly; and manually operated means accessible exteriorly of said casing assembly for governing the operating plane of said valve-operating assembly.

4. In engine construction; a casing formed with separably united valve, cylinder, control and bearing sections, the latter being disposed in longitudinal order about a common axis extending longitudinally through the casing; a crank shaft rotatably supported for rotation about said axis; bearings in said bearing sections in which the ends of said shaft are supported for rotation; pistons slidably mounted in cylinders formed in said cylinder section; connecting rod means uniting said crank shaft with said pistons; a vertical web formed in the valve section of said casing, said web being provided with a plurality of spaced parallel longitudinally extending open-ended chambers; a spool-type valve mounted for sliding movement in each of said chambers; passage means entering the web of said valve section and extending to said chambers and from said chambers to said piston cylinders, said passage means serving to conduct an elastic working fluid under pressure from a source of supply to said cylinders; a variable plane wabble plate assembly disposed within said control section of the casing; means joining said assembly with said valves to produce predetermined reciprocatory movement of said valves in response to the rotation of the wabble plate assembly with said crank shaft; means supporting said wabble plate assembly to maintain the same in different planes of operation with respect to the vertical in controlling the throw of said valves; and manually operated means for adjusting and maintaining the adjustment of said wabble plate in producing valve motion.
